UNITED STATES PATENT OFFICE.

ALEXANDER GILCHRIST HATCH, OF HONOLULU, TERRITORY OF HAWAII, ASSIGNOR TO W-H KEYLESS LOCK COMPANY, LIMITED, OF HONOLULU, TERRITORY OF HAWAII, A CORPORATION OF HAWAII.

KEYLESS LOCK.

Application filed July 14, 1925. Serial No. 43,583.

To all whom it may concern:

Be it known that I, ALEXANDER GILCHRIST HATCH, a citizen of the United States, residing at Honolulu, Territory of Hawaii, have 5 invented certain new and useful Improvements in Keyless Locks; and I do hereby declare the following to be a full, clear, and exact description of the invention, such as will enable others skilled in the art to which 10 it appertains to make and use the same.

This invention relates to keyless locks and has for its principal object to provide a construction whereby the combination necessary to control the movements of the locking bolt 15 may be readily changed at will without the necessity of taking the lock apart and without the use of any tools whatever. While applicable to numerous forms of permutations locks, the present construction is more 20 particularly designed for use with locks in which the locking slide or bolt moves in a direction transversely of the axis of the permutation wheels as distinguished from those in which the locking bolt moves in a direction 25 parallel to such axis and more particularly to such locks as are described and claimed in applicant's Patent No. 1,555,969, of October 6, 1925; applicant's co-pending application Serial No. 708,253, filed April 22, 30 1924; an application, Serial No. 739,665, filed jointly September 24, 1924, by applicant and Meade Wildrick; and an application, Serial No. 746,176, filed October 27, 1924, by Meade Wildrick.

35 The anti-picking guards herein disclosed constitute no part of the invention sought to be protected in this application, but are claimed in applicant's above-mentioned case Serial No. 708,253, and in applicant's co-pending case Serial No. 36,659, filed June 40 12, 1925.

The combination-changing mechanism herein disclosed and specifically claimed is a modification of the combination-changing 45 mechanism disclosed and claimed in applicant's prior application Serial No. 36,660, filed June 12, 1925.

A further object of the invention is to 50 provide a device of the character described which will be simple in construction, comparatively inexpensive to manufacture and install and quite efficient in use.

With the above and other objects in view which will appear as the description pro-

ceeds, the invention consists in the novel 55 details of construction and combinations and arrangements of parts more fully herein-after disclosed and particularly pointed out in the appended claims.

Referring to the accompanying drawings 60 forming a part of this specification, in which like reference characters designate like parts in all the views;

Fig. 1 is a front elevational view of a portion 65 of a lock embodying the present invention;

Fig. 2 is a side elevational view of the parts shown in Fig. 1;

Fig. 3 is a central vertical sectional view 70 of the parts shown in Figs. 1 and 2;

Fig. 4 is transverse sectional view taken approximately on the plane indicated by line 4—4 in Fig. 3;

Fig. 5 is a horizontal sectional view partly 75 in elevation, taken approximately on the plane indicated by the line 5—5 of Fig. 1; and,

Fig. 6 is an expanded detail perspective view of one of the permutation wheels.

As above mentioned, the invention readily 80 lends itself to application to various types of lock and, therefore, the details of the lock casing, locking bolt, etc., have been illustrated more or less diagrammatically since they constitute no special part of the present 85 invention but may be changed in obvious ways, to meet the varying conditions. The lock in each instance, however, will comprise a suitable casing 10 in which is slidably mounted a locking bolt or slide 11 provided 90 with a plurality of fingers 12, each having a laterally projecting locking toe 13 adapted to ride in annular grooves provided in the corresponding permutation wheels as is disclosed in my said co-pending application 95 Ser. No. 698,718.

Suitably mounted in the said casing is a shaft 14 provided adjacent its one end with a hub portion 15 of somewhat increased diameter and with a head 16 provided with a 100 slot 17 for receiving a screw driver for the purpose of assembling. The said hub portion 15 constitutes a journal for one of the permutation wheels 18, the remaining wheels being journaled upon sleeves 19 which are 105 slidably and rotatably mounted upon the said shaft 14. The permutation wheel assembly is maintained in assembled relation

by means of a suitable nut 20 which engages the reduced threaded end 21 of the shaft 14 as will be clear from Fig. 3.

Each permutation wheel 18 comprises a main body portion 22 provided with an axial bore 23 and an axially extending reduced hub 24 provided with detent notches 25, as will be clear from the drawings. The exterior circumference of the member 22 is 10 preferably divided into sectors with longitudinally extending depressions or projections 26 between each of said sectors which may carry a suitable indicating character, not shown, as is well known in the art. The 15 said body members are also recessed upon one face as indicated at 27 and provided with a counter bore 28 forming a shoulder 29 adjacent the bottom of the recess 27. The said members also carry a pair of diametrically opposed axially extending pins or projections 30 which serve to engage the said body members with their companion members, under normal operating conditions, as will appear more fully below.

25 As above stated, the wheels 18 are rotatably mounted either upon the hub portion 15 of shaft 14 or upon the sleeve members 19 carried by the reduced portion of the said shaft and the recessed portion 27 30 of the said body members 22 under normal conditions receives the companion members 32 which are provided with the axial bores 33 and are slidably and rotatably mounted upon the shaft 14, as best shown in Fig. 35. 6. Each of these members is provided upon one flat face with an annular groove 37 from which the radial slot 38 leads to the exterior circumference. This said exterior circumference is in turn provided 40 with a plurality of longitudinally extending grooves 39 and with a radially extending flange or ring 40, which under normal conditions abuts against the shoulder 29 of the member 22, and which prevents longitudinal 45 movement of the inner member 32 when the parts are in the locked positions. In other words, the said flange serves to prevent the changing of the combination when the lock 50 is locked, and it will also prevent such 55 change when the lock is unlocked, except when proper combination is set, i. e., when the toes 13 are in line with the slots 56. The portions of the slots 39 to the right of the said ring or flange 40 serve to receive 60 the pins or projections 30 with which the member 22 is provided, as above described and to form a readily detachable connection between the members 22 and 32, as will be readily understood. On the other hand 65 the portions of the slots 39 to the left of the ring or flange 40 as viewed in Figs. 3 and 6 constitute false slots or recesses adapted to prevent the unauthorized opening of the lock in the manner disclosed in the co-pending application of Meade Wil-

drick, Serial Number 746,177, filed October 27, 1924.

Interposed between adjacent permutation wheels 18 is an annular shield member 45 provided with a longitudinally extending slot 46 to accommodate the finger 12 of the locking bolt and with an integral resilient tongue 47 constituting a detent spring adapted to coact with the detent notches 25 of the wheels to retain the latter in desired positions as is readily understood. The primary function of these shield members is to prevent the introduction of a relatively thin instrument into the apertures in the casing 10 through which the wheels 18 project whereby it might be possible to feel the location of the notch or slot 38 in each of the wheel members 32 and to thus pick the lock. The action of these shield members is more particularly described and they are specifically claimed in my co-pending application, Ser. No. 36,659, filed June 12, 1925.

The shaft 14 is longitudinally slidably mounted in the casing 10 and it is adapted to be held in either of two longitudinally adjusted positions by means of a spring member 50 which engages a pair of separate grooves 51 and 52 provided on the hub 15 adjacent the head 16. In other words, when the shaft 14 and its associated parts are in one position the spring member 50 will occupy one of the said grooves while when the shaft and its associated parts are in the other position, said spring member will occupy the other of said grooves.

The operation of the device is as follows:

Under normal operating conditions the parts occupy the positions illustrated in Fig. 3 of the drawing, for example, and when in these positions each of the wheels 18 may be turned to set or destroy the combination in the same manner as the ordinary permutation lock. If, however, for any reason, it is desired to change the relative positions of the bolt accommodating slots 38 and the indicia carried by the respective wheels 18 it is only necessary to slide the shaft 14 toward the left as viewed in Fig. 3, by a manual pressure against the right hand end of the said shaft which will cause the spring 50 to occupy the groove 52 instead of the groove 51. This longitudinal motion of the shaft will be transmitted through the shoulder 55 formed by the hub 15 to the member 32 of the right hand wheel 18 and also through the sleeves 19 to the corresponding members 32 of the other wheels 18. The members 22 of the said wheels, however, will not move, inasmuch as they are retained against axial movement due to their projection through the apertures in the front of the casing 10, and also due to shield members 45 which space them from each other and from the casing. Dur-

ing this longitudinal movement of the parts, the toes 13 of the locking bolt fingers 12 will enter into recesses or holes 56 provided in the members 32 which recesses are preferably so positioned that the longitudinal movement above referred to of the parts, may only be accomplished when the combination has been previously set.

This longitudinal movement of the shaft 10 14 and the members 32, while the members 22 remain stationary, will serve to disengage the pins or projections 30 carried by the last named members from the slots or recesses 39 and when this disengagement is accomplished the members 22 may be freely 15 rotated upon their journals without their motion being transmitted to the members 32. It thus results that the relative circumferential positions of the members 22 and 32 may 20 be changed at will and when the desired new combination has been obtained, by manually returning the shaft and the members 32 toward the right as viewed in Fig. 3 to the positions shown therein, the pins 30 will 25 again enter the slots or recesses 39 and the wheel members 22 and 32 locked together for circumferential movement.

It will thus be seen that this invention 30 provides a construction whereby it is possible to readily change or shift the combination necessary to control the locking bolt of a permutation lock by a simple manual movement of the parts and entirely without the use of tools, or the disassembling of the lock.

While one form of the invention has been 35 illustrated and described it is obvious that those skilled in the art may vary the precise details of construction as well as the arrangements of parts without departing from the spirit of the invention and therefore, it 40 is not wished to be limited to the above disclosure except as may be required by the claims.

What is claimed is:

1. A keyless lock comprising a casing and a lock mechanism mounted therein, said mechanism including a bolt movably mounted in said casing, a plurality of permutation tumblers rotatable about axes disposed cross-wise with respect to the direction of movement of said bolt and each comprising a concealed lock-controlling element and a tumbler-setting element exposed for manipulation through an opening in said casing, couplings normally preventing relative rotational movement between the elements of

said tumblers, said couplings being capable of being disabled by relative lateral movement of said tumbler elements, means preventing lateral movement of said tumbler-setting elements and coupling disabling means, accessible from the exterior of the assembled lock, whereby said lock-controlling elements may be moved laterally to disable said couplings, thereby permitting the 60 combination of said lock to be readily changed by merely moving said tumbler-setting elements to any desired positions relative to their respective lock-controlling elements, said bolt and lock-controlling elements having opposed parts obstructing lateral movement of the latter for the purpose of disabling said couplings except when said tumblers have been set in a predetermined 65 relation and said bolt moved to a predetermined position. 70

2. In a keyless lock, a casing; a shaft longitudinally slidably mounted in said casing; a locking bolt also slidably mounted in said casing for movement in a plane transversely of the axis of said shaft, said bolt having a plurality of locking toes; a plurality of permutation wheels, each comprising a bolt controlling member and an indicia bearing member normally connected together, said bolt 80 controlling members having an annular groove and a radial slot accommodating said toes, said indicia bearing members being held against longitudinal movement; and spacing members on said shaft between said bolt controlling members, and constituting journals 90 for said indicia bearing members.

3. In a keyless lock, a casing; a shaft longitudinally slidably mounted in said casing; a locking bolt also slidably mounted in said casing for movement in a plane transversely of the axis of said shaft, said bolt having a plurality of locking toes; a plurality of permutation wheels, each comprising a bolt controlling member and an indicia bearing 100 member normally connected together, said bolt controlling members having an annular groove and a radial slot accommodating said toes, said indicia bearing members being held against longitudinal movement; spacing members on said shaft between said bolt controlling members, and constituting journals for said indicia bearing members; and means for yieldably holding said shaft in different longitudinal positions. 105

ALEXANDER GILCHRIST HATCH.
